CLAIM

I claim the ornamental design for a terminal crimp socket, as shown and described.

DESCRIPTION

FIG. 1 is a top perspective view of a terminal crimp socket, showing my new design;

FIG. 2 is a top plan view thereof;

FIG. 3 is a bottom plan view thereof;

FIG. 4 is a right-side elevational view thereof;

FIG. 5 is a left-side elevational view thereof;

FIG. 6 is a rear elevational view thereof;

FIG. 7 is a front elevational view thereof; and,

FIG. 8 is a bottom perspective view thereof.
